UNITED STATES PATENT OFFICE.

JAMES GEORGE WILLCOX ALDRIDGE, OF LONDON, ENGLAND.

APPARATUS FOR CHARGING AND DISCHARGING GAS RETORTS.

Application filed August 31, 1923. Serial No. 660,335.

To all whom it may concern:

Be it known that I, JAMES GEORGE WILLCOX ALDRIDGE, a British subject, residing at London, England, whose post-office address

5 is No. 39 Victoria Street, London, S. W. 1, have invented certain new and useful Improvements in Apparatus for Charging and Discharging Gas Retorts, of which the following is a full, clear, and exact description, 10 such as will enable others skilled in the art to which it appertains to make and use the same.

This invention relates to retort charging apparatus of the type that comprises a central member provided with laterally-projecting push plates combined with said central member in such a way that they will co-operate with each other to form a series of 15 pockets on each side of said central member that hold material which is to be introduced into a retort by the forward stroke or charging stroke of said central member and will swing upwardly relatively to said member in such a way, during the return stroke or rearward stroke of said member, that they will slide or drag over the top surface of the material that has been deposited in the retort. I have herein illustrated my invention embodied in an apparatus of the 20 kind known commercially as a "charging-discharging apparatus" that is adapted to be used in connection with open-ended retorts for introducing fresh material into an open-ended retort simultaneously with the operation of discharging the residue of the previous charge through the rear end of the retort. I wish it to be understood, however, that my broad idea is not limited to an 25 apparatus of the particular type mentioned, but is applicable to any retort charging apparatus of the kind that comprises a central member equipped with laterally-projecting elements which push material into the retort during the forward stroke of said member and swing upwardly on the reverse stroke of said member into a substantially horizontal position between the crown of the 30 retort and the top surface of the material that has been deposited in the retort.

One object of my present invention is to provide a retort charging apparatus of the general type mentioned, in which the push plates or laterally-projecting elements at the sides of the central member are of such form

and arrangement that they permit a larger charge or a charge of greater volume or weight to be introduced into the retort.

Another object is to provide a push plate 60 for a retort charging apparatus which is of such cross sectional shape that it is stronger and more rigid than the push plates now used on retort charging apparatus.

And still another object is to provide a retort charging apparatus of the general type mentioned in which the central member that carries the push plates is provided with laterally-projecting guides that co-operate 65 with the sides of the retort to prevent the ends of the push plates from rubbing against the sides of the retort during the operation of introducing the charge into the retort. Other objects and desirable 70 features of my invention will be hereinafter pointed out.

Figure 1 of the drawings is a perspective view, illustrating a portion of my improved apparatus arranged in operative position in 80 a retort, the retort being broken away.

Figure 2 is a perspective view of one of the push plates.

Figure 3 is a transverse sectional view of 85 the apparatus, showing the push plates in the position they occupy during the forward stroke or charging stroke of the central member that carries the push plates.

Figure 4 is a transverse sectional view, 90 showing the push plates in the position they occupy during the rearward stroke or return stroke of said central member; and

Figure 5 is a perspective view, illustrating 95 a modified form of push plate.

Referring to the drawings, A designates the central member of the apparatus which may consist of a long, rigid member or a member composed of a number of short sections 1 joined or hinged together in such a 100 way that it can be wound onto and off of a polygonal-shaped wheel during the operation of introducing said member into a retort and withdrawing said member from the retort. The member A is provided with a plurality of pairs of push plates or pushing elements B arranged at the opposite side of said central member in such a way that they will be disposed vertically at substantially right angles to said central member 105 when said member is moved forwardly into a retort x, as indicated by the arrow 110

2
in Figure 1, thus forming series of pockets at the opposite sides of said central member that hold the material which is to be deposited in the retort. The push plates 5 B are hinged or pivotally mounted on the central member A in such a way that they will swing upwardly towards the crown of the retort into a substantially horizontal position, as shown in Figure 4, when the 10 central member A starts to move rearwardly on its return stroke. In the form of my invention herein illustrated the central member A is provided with pairs of horizontally-disposed hinge pins 2 that project laterally from the opposite sides of said member adjacent the top edge of same, and each of the push plates is oscillatingly mounted on one of said hinge pins by a hinge element 3 that can be formed conveniently by 15 a flat iron bar bent to produce an eye that surrounds the hinge pin, and a depending shank or downwardly-projecting portion 3^a that is riveted or otherwise connected to the push plate with which it co-operates. 20 During the forward or charging stroke of the member A the push plates B are prevented from swinging rearwardly by laterally-projecting stops 4 on the central member, as shown in Figure 1, but when the 25 direction of movement of said central member is reversed to withdraw it from the retort, the push plates B swing upwardly and thereafter drag or slide over the top surface of the material that has been deposited in 30 the retort.

One object of my present invention is to improve the form and construction of the push plates B, whereby they shall be made more effective during the forward stroke or 40 charging stroke and their withdrawal on the return stroke facilitated, thus permitting an increased charge to be deposited in the retort, as compared with retort charging apparatus of the kind now in general 45 use.

I accomplish this by making the push plates B of such form that the upper outer end portion of each push plate is offset rearwardly, so as to permit the push plates to 50 rise higher or closer to the crown of the retort during the return stroke or withdrawal stroke of the central member A than is possible with a flat push plate whose upper outer end portion lies in the same plane as 55 the main body of the push plate. To state it in another way, each of the push plates B is of such shape that the plane of the outer portion of the plate adjacent to the side of the retort is set back in relation to the other 60 portion of the plate, so that the upper outer end portion of the plate will not strike against the side of the retort when the push plate swings upwardly into a horizontal position substantially parallel to the top or 65 crown of the retort. This is a distinct ad-

vantage, in that it produces a charging apparatus which is capable of handling a charge of greater weight or volume than can be handled by an apparatus of the kind that is equipped with straight push plates, 70 as is now the usual practice.

Preferably, each of the push plates B is provided with two substantially right-angularly-disposed bends 5 and 5^a that extend downwardly from the upper edge of the plate towards the lower edge of the plate, as shown in Figure 2, thus producing a push plate whose upper outer end portion 6 is set back or deflected rearwardly with relation to the inner end portion 7 of the plate to which the hinge member of the plate is connected. Preferably, the rearwardly offset portion 6 of the push plate is set back a gradually diminishing degree from the top edge towards the lower edge 80 of the push plate, so that the two portions 6 and 7 of the push plate will merge into one plane at the lower edge of the push plate. In addition to increasing the upward throw of the push plate, the right-angularly-disposed bends in the plate increase the rigidity of the plate and make it materially stronger than a flat plate, thus eliminating the possibility of the plate becoming bent out of shape by the strain or pressure exerted on same by a relatively 85 large charge that the plate is pushing into the retort.

Instead of making the push plates B of the form shown in Figure 2, the upper outer end portion of each push plate may be curved at 8, as shown in Figure 5, so as to clear the retort or not strike against the retort when the plate swings upwardly into an approximately horizontal position during the return stroke or withdrawal stroke of the central member A.

As previously stated, it is immaterial whether the central member consists of a long, rigid member or a jointed member 100 made up of a number of short sections. In view of the fact that the apparatus is designed to handle relatively large charges of material, it is essential that the central member be of very rigid construction, and therefore, I prefer to form said member from hollow, bar-like castings pivotally connected together by pivot pins 1^a, as shown in Figure 1, and each provided at its bottom edge with a renewable wear piece 9 105 formed by a shoe of substantially channel shape in cross section whose side flanges embrace a reduced portion 1^b on the bottom edge of the casting.

In order to prevent the outer edge portions of the push plates B from rubbing against the sides of the retort, I provide the central member A with laterally-projecting arms C that serve as guides or fenders which are of such length that they prevent 110

the outer edges of the push plates B from rubbing against the sides of the retort during the forward stroke or return stroke of the central member. These fenders or guides C can be constructed in various ways and arranged at various points on the central member, but I prefer to construct them in the form of substantially horizontally-disposed arms that project laterally from the upper edge of the central member A and which are provided at their outer ends with renewable wear pieces 10, as shown in Figure 1, that co-operate with the sides of the retort to center the apparatus relatively to the retort and hold the outer edges of the push plates out of contact with the sides of the retort.

Having thus described my invention, what I claim as new and desire to secure by Letters Patent of the United States is:

1. A retort charging apparatus, comprising a central member that is adapted to be introduced into and withdrawn from a retort, push plates at the sides of said central member hinged at their upper edges to horizontally-disposed pivots, and means for maintaining said push plates in an upright position at approximately right angles to said central member during the forward stroke of said member, the upper outer edge portions of said push plates being deflected rearwardly so as to clear the retort when said plates swing upwardly into a horizontal position during the return stroke of said central member.

2. A retort charging apparatus, comprising a central member adapted to be introduced into and withdrawn from a retort, and hinged push plates arranged at the sides of said central member and combined with same in such a way that they will be disposed vertically, transversely of the retort during the forward stroke of said central member and will swing upwardly into a horizontal position in proximity to the crown of the retort during the return stroke of said central member, each of said push plates being provided intermediate its lateral side edges with an angularly-disposed portion so as to cause the upper outer end portion of the plate that lies adjacent to the side of the retort to be offset rearwardly or set back with relation to the upper inner portion of the plate that lies adjacent to the central member.

3. A retort charging apparatus, comprising a central member adapted to be introduced into and withdrawn from a retort, and hinged push plates arranged at the sides of said central member and combined with same in such a way that they will be disposed vertically transversely of the retort during the forward stroke of said central member and will swing upwardly into a horizontal position in proximity to the

crown of the retort during the return stroke of said central member, each of said plates having two substantially right-angularly-disposed bends that extend downwardly from the upper edge of the plate towards the bottom edge of the plate but which terminate above said bottom edge, thereby causing the upper outer edge portion of the plate that lies adjacent to the side of the retort to be offset rearwardly or set back with relation to the other portion of the plate.

4. A retort charging apparatus, comprising a central member that is adapted to be introduced into and withdrawn from a retort, laterally-projecting hinge pins on said central member, and push plates arranged at the sides of said central member and provided with hinge members that are oscillatingly mounted on said hinge pins, each of said push plates having its upper outer edge portion offset rearwardly or set back with relation to the portion of the plate connected to the hinge member.

5. A retort charging apparatus, comprising a central member adapted to be introduced into and withdrawn from a retort, push plates at the sides of said member that are arranged in an upright position at substantially right angles to said member during the forward stroke of said member, and laterally-projecting fenders or guides on said member that are adapted to co-operate with the sides of the retort to prevent the outer edges of the push plates from rubbing against the retort.

6. A retort charging apparatus, comprising a central member adapted to be introduced into and withdrawn from a retort, hinged push plates at the sides of said member, and transversely-disposed fenders or guides on said member provided at their outer ends with renewable wear pieces that are adapted to co-operate with the sides of the retort to prevent the side edges of the push plates from contacting with the sides of the retort.

7. A retort charging apparatus, comprising a central member adapted to be introduced into and withdrawn from a retort and provided with hinged push plates arranged at the opposite sides of said member, said member being composed of a plurality of sections hinged together and each formed by a hollow, bar-like casting, and a renewable element on the bottom edge of each of said sections composed of a substantially channel-shaped shoe whose side flanges embrace a reduced portion on the casting.

8. A retort charging apparatus, comprising a central member adapted to be introduced into and withdrawn from a retort, hinged push plates on said member arranged at the sides of same and each having its upper outer edge portion deflected rear-

wardly, for the purpose described, and transversely-disposed guides or fenders on said central member that are adapted to co-operate with the sides of the retort to hold the outer edges of the push plate out of contact with the sides of the retort.

9. A retort charging apparatus, comprising a central member adapted to be introduced into and withdrawn from a retort, hinged push plates on said member arranged at the sides of same and each having its upper outer edge portion deflected rear-

wardly, for the purpose described, transversely-disposed guides or fenders on said central member that are adapted to co-operate with the sides of the retort to hold the outer edges of the push plate out of contact with the sides of the retort, said central member being composed of a plurality of sections pivotally connected together, and a substantially channel-shaped shoe or wear piece arranged at the lower edge of each of said sections.

JAMES GEORGE WILLCOX ALDRIDGE.
